COMBINATION TALCUM POWDER CONTAINER AND BRUSH DISPENSER OR SIMILAR ARTICLE

Edward W. Beatty, Chicago, Ill., assignor to Richard G. Krueger, Inc., New York, N. Y., a corporation of Delaware

Application June 16, 1958, Serial No. 51,388

Term of patent 14 years

(Cl. D58—17)

Fig. 1

Figure 1 is a front elevational view of a combination talcum powder container and brush dispenser or similar article showing my new design;

Figure 2 is an elevational view of one side thereof, the opposite side being the same; and

The dominant feature of the design resides in the portions shown in full lines.

I claim:

The ornamental design for a combination talcum powder container and brush dispenser or similar article, substantially as shown and described.
